GUIDING OF BELTS IN HIGH-DRAFT MECH-
ANISMS

Fernando Casablancas, Lausanne, Switzerland

Application September 8, 1936, Serial No. 99,823
In Spain September 20, 1935

8 Claims. (Cl. 19—131)

In high-draft mechanisms working with endless belts, difficulties are sometimes encountered in obtaining a correct movement of the belts without lateral deviation, particularly when these 5 belts are of relatively great width, as in the case of drawing frames and other spinning mechanisms.

When the belts are of small width, as is generally the case in continuous spinning machines, 10 for correctly guiding the belts the usual frame formed by two lateral plates conveniently connected together and resting on the same cylinders as carry the belts, are generally sufficient; the said plates guide the belts laterally so as to prevent displacement thereof, and support a number 15 of guide rods which guide the belts by the curve which they form at the front. On the other hand, when use is made of belts of relatively great width, as is particularly the case in drawing frames, this frame is generally not sufficient 20 to guide the belts suitably and it occurs that, owing to the differences in thickness and hardness of the material of which the belts are made, the latter are deformed or lengthened more on one side than on the other and are inclined or 25 displaced from their correct position, the lateral plates of the frame not being sufficient to prevent this displacement of the belts. In some cases, this displacement reaches such a degree that the friction between the edge of the belt and the plate 30 of the frame not only wears away the belt, but also the plate.

The present invention relates to improvements 35 in the guide rods of the belts and in the manner of mounting these guide rods with the object of bringing it about that when the belt is inclined the guide rod automatically compensates for the deviation of the belt.

These improvements consist in mounting the 40 guide rods of the front curve of the belts in such a manner that they may oscillate or be inclined with respect to their normal position in order to compensate for any lateral displacement or stretching of the belts. To this end, each guide 45 rod is preferably constructed of two parts, one of which fits into the frame in the usual manner and remains fixed during the operation of the machine, while the other part is mounted on the first part and may have an oscillatory movement, it being the latter which actually guides 50 the belt. By reason of this arrangement, the movable part of the guide rod may be inclined to a greater or lesser extent while oscillating on the fixed part.

55 In the simpler form of construction, the

stretching of the belt produces the inclination of the guide rod which automatically compensates for this stretching, and in other forms of construction there are combined with the movable part of the guide rod, contact members and parts which are actuated by the belt when a lateral displacement is set up therein and thus bring about the inclination of the guide rod in order to compensate for this lateral displacement and to cause the belt to return to the correct position.

Various constructional forms of the oscillating guide rods according to the present invention are illustrated in the accompanying drawings, in which:

Figure 1 is a central vertical section of the two belts provided with oscillating guide rods according to this invention.

Figure 2 is a longitudinal section of the same on the line II—II of Figure 1.

Figure 3 is a detail view from above of a guide rod.

Figure 4 is a view from above of another constructional form of the oscillating guide rod.

Figure 5 is a section of this guide rod on the line V—V of Figure 4.

Figure 6 is a similar view to Figure 4, but indicating how the guide rod oscillates upon displacement of the belt.

Figure 7 is a view from above of a third form of construction seen in the direction of the arrow VII of Figure 8 and

Figure 8 is a cross section on the line VIII—VIII of Figure 7.

In the constructional form illustrated in Figures 1 to 3, 1 and 2 designate the two cylinders actuating the belts 3 and 4 in the known manner, the said belts being guided at the front part by means of guide rods introduced into the curve of the belts, which are designated in Figure 1 by 5.

Each of these guide rods 5 is formed of two parts, as is shown in particular in Figure 3. The part 7 forms a plane guide rod, which fits into grooves in the lateral plates 6 of the frame in the known manner, and remains fixed during the operation of the mechanism. This rod 7 is, according to the invention enclosed by an outer rod 8 of U-shaped section, which is articulated to the rod 7 by a pin 9.

Owing to this arrangement, the fixed rod 7 remaining fixed in the grooves of the lateral plates 6 of the frame, the outer rod 8 constituting the actual guide of the belt may oscillate and turns about the pin 9, taking up a more or less inclined position which is thus automatically adapted to 55

the stretching to which the belt 4 may be subjected. In this way, the belt 4 is suitably guided over its entire width, and any stretching which is set up, is prevented from causing any lateral displacement of the belt.

In the form of construction illustrated in Figures 4 to 6, the guide rod 7, which fits into the recess in the frame, is also enclosed by means of a casing of U-shaped section 8, which guides the belts, but this casing 8, instead of being articulated to the rod 7 as in the previous case, is provided with two apertures 10 inclined in opposite directions, into which are introduced pins 11 secured to the inner rod 7 in such a manner that upon sliding of the rod 8 in the lateral direction the inclination of the two slots 10 forces this rod 8 to be inclined as shown in Figure 6.

In combination with this arrangement the outer rod 11 has at its extremities lateral projections 12, as shown in Figure 5, with which the lateral edge of the belt 4 lightly comes into contact, so that when for any reason the belt is displaced laterally as shown in Figure 6, it causes the rod 8 to be shifted laterally and consequently the slots 10 cause this rod to be inclined and to take up a position which arrests the displacement of the belt and tends to centre it.

In Figures 7 and 8, a third form of construction is shown, in which the rod 7 fits into recesses in the frame 6 and is also enclosed by an outer rod or casing 8 of U-shaped section, the said casing 8 being articulated to the rod 7 by a central pin 9, as in Figures 1 to 3.

In order to determine the inclination of this rod 8, there is in this case disposed on each side of the frame a disc or sector 14 adapted to rotate about a spindle or pin 15 in the frame and disposed in such a manner that if the belt 3 is displaced its edge touches the sector 14 and causes it to rotate. This sector 14 is coupled by a connecting rod 16 with the oscillating rod 8.

In this arrangement, it is also brought about that upon lateral displacement the belt 3 touches the sector 14 on one side or the other and causes it to rotate, whereupon this sector, through the intermediary of the connecting rod 16, causes the outer rod 8 to oscillate and take up an inclined position which arrests the lateral deviation of the belt and tends to re-centre it.

50 In the drawings, it has been assumed that the rod 7 is of solid section and the movable rod 8 is of stamped sheet metal of U-shaped section partially embracing the fixed rod 7.

What I claim is:

55 1. In a high-draft mechanism for textile fibres the combination of endless belts, cylinders for actuating said belts, a guiding frame, lateral plates in the said frame, guide rods introduced into the front curve of the belts, and belt engaging rods articulated to said guide rods and adapted to oscillate with respect to their normal position in order to compensate for the stretching and displacement to which the belts might be subjected.

60 2. In a high-draft mechanism the combination of an endless belt, a cylinder for actuating said belt, a guiding frame including lateral plates, and a guiding member inserted through the front curve of the said belt and consisting in a rod 70 attached to said lateral plates and a belt contacting rod articulated at its middle with said rod, said contacting rod adapted to oscillate to

compensate for stretching and lateral displacement of the said belt.

3. In a high-draft mechanism for textile fibres the combination of endless belts, cylinders for actuating said belts, a guide frame, lateral plates 5 in said frame, fixed guide rods introduced into the front curve of the belts, and oscillatable belt engaging rods articulated to said fixed guide rods for movement with respect to their normal position in order to compensate for the stretching 10 and displacement for which the belts might be subjected.

4. In a high-draft mechanism for textile fibres the combination of endless belts, cylinders for actuating said belts, a guiding frame, lateral 15 plates in said frame, said plates having corresponding recesses, fixed guide rods introduced into the front curve of the belts and fitting in the recesses in said lateral plates, and belt engaging 20 rods articulated to said guide rods and adapted to oscillate with respect to their normal position in order to compensate for the stretching and displacement to which the belts might be subjected.

5. In a high-draft mechanism for textile fibres the combination of endless belts, cylinders for actuating said belts, a guiding frame, lateral plates in said frame, fixed guide rods in the front curve of the belts, and oscillatable belt engaging rods of U-shaped section articulated to the fixed 25 rod to compensate for the stretching and displacement to which the belts might be subjected.

6. In a high-draft mechanism for textile fibres the combination of endless belts, cylinders for actuating said belts, a guiding frame, lateral plates in said frame, fixed guide rods in the front 35 curve of the belts, and oscillatable belt engaging rods of U-shaped section, said oscillatable rods positioned over the fixed rods and having two slots in one side inclined in opposite directions, said fixed rods having pins corresponding in position to said slots and adapted to fit into said slots, said oscillatable rods carrying lateral projections 40 for coming into contact with the belts whereby a lateral displacement of a belt causes an oscillatable rod to slide laterally on said pins to compensate for the deviation of the belt.

7. In a high-draft mechanism for textile fibres the combination of an endless belt, means for actuating said belt, a guiding frame, lateral plates in the said frame, a fixed guide rod introduced 50 into the front curve of the belt, and a belt engaging rod articulated to said guide rod and adapted to oscillate with respect to its normal position in order to compensate for the stretching and displacement to which the belt might be subjected.

8. In a high draft mechanism for textile fibres the combination of endless belts, cylinders for actuating said belts, a guide frame, lateral plates in said frame, fixed guide rods in the front curve 60 of the belts, oscillatable belt engaging rods articulated to said fixed guide rods for movement with respect to their normal position, discs mounted in the frame at the sides of the belts and adapted to be rotated by contact with the edge of a belt if the belt is laterally displaced, and connecting rods between the discs and the extremities of the oscillatable rods to move the latter in order to compensate for the stretching 65 and displacement of the belts.
